US00D609382S

(12) **United States Design Patent**
Laporte

(10) **Patent No.:** **US D609,382 S**
(45) **Date of Patent:** **** Feb. 2, 2010**

(54) **LUMINAIRE**(75) Inventor: **Jean-Francois Laporte**, Boisbriand (CA)(73) Assignee: **Lumec Inc.**, Boisbriand, Quebec (CA)(**) Term: **14 Years**(21) Appl. No.: **29/307,000**(22) Filed: **Apr. 21, 2008**(51) LOC (9) Cl. **26-05**(52) U.S. Cl. **D26/71**(58) Field of Classification Search **D26/67-72, D26/85, 92; 362/145, 152, 183, 294, 373, 362/414, 431, 545**

See application file for complete search history.

(57) **CLAIM**

The ornamental design for a luminaire, as shown and described.

DESCRIPTION

FIG. 1 is a lower perspective view of the luminaire of the present invention;

FIG. 2 is a right side view of the design of the present invention;

FIG. 3 is a front view of the design of the present invention;

FIG. 4 is a rear view of the design of the present invention;

FIG. 5 is a top view of the design of the present invention; and,

FIG. 6 is a bottom view of the design of the present invention.

The broken lines showing environmental structure are for illustrative purposes only and form no part of the claimed design.

1 Claim, 6 Drawing Sheets# US D609,382 S
